Re. 16,093

UNITED STATES PATENT OFFICE.

THOMAS FORD WILSON, OF CRANSTON, RHODE ISLAND.

DESIGN FOR A CRANK-CASE ARM.

Original No. 58,387, dated October 11, 1911, Serial No. 345,901, filed December 18, 1912. Application for reissue filed June 9, 1925. Serial No. 6,454. Term of patent 14 years.

To all whom it may concern:

Be it known that I, THOMAS F. WILSON, a citizen of the United States, residing at Cranston, in the county of Providence and State of Rhode Island, have invented a new, original, and ornamental Design for Crank-Case Arms, of which the following is a specification, reference being had to the accompanying drawing, forming part thereof.

In the drawing:

Fig. 1 is a perspective view showing my invention.

Fig. 2 is a side face elevation thereof, and Fig. 3 is an edge view thereof.

I claim:

The ornamental design for a crank case arm, as shown.

THOMAS FORD WILSON.
